J. D. POSNER.

LADY'S GARMENT.

APPLICATION FILED NOV. 8, 1915.

1,198,762.

Patented Sept. 19, 1916.

UNITED STATES PATENT OFFICE.

JACOB D. POSNER, OF NEW YORK, N. Y.

LADY'S GARMENT.

1,198,762.

Specification of Letters Patent. Patented Sept. 19, 1916.

Application filed November 8, 1915. Serial No. 60,245.

To all whom it may concern:

Be it known that I, JACOB D. POSNER, a citizen of the United States, residing at New York city, in the county of New York and State of New York, have invented new and useful Improvements in Ladies' Garments, of which the following is a specification.

This invention relates to certain novel and useful improvements in ladies' garments.

In the present instance I have shown my invention in the form of a nether undergarment which embodies the characteristics and advantages of a skirt or petticoat, both in appearance and effect, combined with the features and functions of a bifurcated garment such as bloomers, knickers, drawers or pantalettes so that in actual practice my article of apparel will, as a unitary structure serve the purpose of both a bifurcated garment and a skirt. I wish it to be understood, however, that the invention is not limited to a garment adapted to be used as an underskirt, as it may also be made up for use as an outer or overskirt, furthermore it may be embodied in the form of a union garment, that is to say one wherein a waist, corset cover, chemise or other upper garment is formed integral with or united to the skirt section or nether garment.

In carrying out my invention I have in view, among other purposes, the provision of a garment which, while forming a complete skirt or petticoat both in appearance and effect, also constitutes a closed garment which will serve to protect the person of the wearer against the elements, and which will possess all of the conveniences and freedom of movement, as well as the capabilities of a bifurcated garment, so that when embodied for instance in the form of an undergarment it may be used as a substitute for and replace all other articles of wearing apparel customarily worn as undergarments.

Still a further object of the invention is the provision of an article of apparel which may be made from any material commonly used in the construction of ordinary undergarments, and which may be ornamented in any preferred manner, as by the use of laces, embroidery, ribbons, frills, ruchings and the like. Furthermore, when embodied in the form of an outer garment it may be constructed of any suitable material and modi-

fied as advisable to adapt it for a particular use such as a walking, riding or gymnasium habit.

Another object of the invention is the provision of a garment which when constructed as a union undergarment will dispense with the necessity of wearing such undergarments as corset covers, chemise and the like.

Furthermore, I propose to provide a garment which is equipped with garters which not only act to secure the stockings but also serve to enable the skirt to be adjusted so as to be lengthened or shortened as desired.

It is also my purpose to provide a garment of this type which will embody the desired features of simplicity, comfort and convenience, which will not bind upon the person of the wearer, nor hinder nor limit the freedom of movement of the latter, and which when worn will present a neat, attractive and stylish appearance.

With the above recited objects, and others of a similar nature in view, my invention consists in the construction, combination and arrangement of parts set forth in and falling within the scope of the appended claims.

In the accompanying drawings: Figure 1 is a front view of my garment embodied in the form of an underskirt and showing how it appears when worn by a person assuming a straight standing position. Fig. 2 is a similar view showing the appearance of the skirt when the limbs of the person are spread apart a relatively great distance. Fig. 3 is a view in side elevation and also showing the garment upon the wearer. Fig. 4 is a plan view of the blank or piece of material from which the skirt is made, the final shape of the blank being shown in full lines. Fig. 5 is a view in front elevation showing the skirt in spread position with a portion of the front of the skirt broken away to illustrate the location of one of the garters. Fig. 6 is a horizontal sectional view taken through the skirt on the line 6—6 of Fig. 5 looking in the direction of the arrows. Fig. 7 is a plan view showing one form of blank or piece of material from which the inserts of the leg sections of the garment may be made. Fig. 8 is a similar view of another form of blank for making the inserts of the leg sections. Fig. 9 is a perspective view showing the invention embodied in one form

of union garment and showing it as it appears upon the wearer.

Referring to the accompanying drawings in detail, and particularly to Figs. 1 to 8 thereof, wherein the invention is shown as embodied in an underskirt or nether garment, the letter A indicates the garment as an entirety while 1 designates the waistband by means of which the garment is fastened on the wearer. This waistband may be made of any preferred material, either elastic or inelastic, and the ends of the band above the back or placket opening 8 of the skirt may be connected together in any suitable manner as by means of hooks and eyes, buttons or the like.

In the cutting or making up of the skirt I use a piece or section of a selected material, such as cloth, silk or other fabric, preferably cutting from the bolt of material a rectangular section such as is indicated in dotted lines in Fig. 4 and designated by the letter B. This piece of material B is then preferably cut as indicated in full lines in Fig. 4, that is to say one of the transverse edges is cut slightly concave as shown at 3 while the opposite transverse edge is cut slightly convex as shown at 4. The piece of material is then preferably folded or doubled on the central transverse line as indicated by dotted lines in Fig. 4, the folded edge so resulting subsequently constituting the bottom edge 5 of the skirt. When so folded, the edge 4 will lie substantially even with the edge 3, and the corners are cut or rounded as shown at 5' to accommodate the curvature of the hips. Each longitudinal side of the folded or doubled material is also cut laterally as at 6 at a point above the bottom folds and then cut downward and outward or on a bias through such bottom folds as at 7, so that a two-ply triangular piece of material is removed from each side adjacent the bottom or folded edge. If the piece of material be now unfolded it appears as shown in full lines in Fig. 4 with the exception of the longitudinal incision 8 which is cut in the half section 9 of the fabric which forms the back of the skirt, the front of said skirt being of course formed by the other half section of the fabric indicated at 10.

When the piece of material B has been folded and cut as described the adjacent side edges are united by stitching from the corner points 11 at the waist to the side points 12 at the leg openings C the latter being formed by the cutting away of the material at the bottom side portions as before described. These leg openings C are covered or provided with insert sections D as clearly shown in the drawing. These insert sections D may be of any preferred material such as lace or silk, and may be ruffled, gathered, plaited or ornamented in

any manner to suit the individual taste. Or, if desired, these insert sections may be made of the same material as the garment itself. One manner of constructing and applying an insert section is to take a rectangular piece of material such as is shown at 13 in Fig. 7 and stitch the upper edge 14 thereof around the top marginal edge of a leg opening, the side edges 15 of the insert section being stitched to the inclined or bias cut side marginal edges of the opening, the bottom edge 16 of the insert section preferably reaching or falling to the level of the bottom edge 5 of the skirt. Of course, when a rectangular piece of material is used for the insert it is gathered or tucked as may be required to cause it to fit, flare and drape properly when attached. However, I prefer to make each insert section D in the general shape of a segment as shown at 17 in Fig. 8, the concave top edge 18 being stitched to the top marginal edge of the leg opening while the oppositely inclined side edges 19 are stitched to the side marginal edges of such leg opening so that the rounded bottom edge 20 of the insert section will drop or fall to the bottom edge 5 of the garment proper. It will be evident, of course, that when attached to the body of the garment these insert sections are opened at the bottom and serve to cover the leg openings and the portions of the limbs of the wearer inserted therethrough.

The garment is further preferably, but not necessarily, provided with the band 100 garters 21, stitched or otherwise secured at or adjacent to the top marginal edges of the leg openings and on the inside of the skirt. Furthermore, these garters when employed are preferably, but not necessarily, made of 105 elastic material, and in addition to serving the purpose of holding up the stockings, also enable the person to adjust the skirt as to length as will be readily understood.

By forming the leg openings as described, perfect freedom of movement of the limbs is permitted and the garment may be put on and taken off as readily as an open skirt. By cutting the openings on a bias as described, the insert sections when applied will 110 drape and flare downward and outward so that the bottom edges of the insert sections fall to the line of the folded or doubled edge of the skirt and practically form a continuous edge with the latter. Furthermore, by so cutting the leg openings on the bias the material of the garment will fall away from the legs thus giving freedom of movement and eliminating the annoyance of the material of the garment clinging around the legs as is incident to a wide, full skirt. It will also be noted that the sides of the skirt proper, extending from the waist points 11 to the points 12 form sides shorter than the 115 length of the skirt from the waistband to 120

the bottom edge 5 so that the garment has the freedom of bloomers so far as knee movement and the like is concerned.

5 The waistband of the skirt may be of any desired character.

In Fig. 9 I have shown my invention as embodied in a union garment, in this case the corset cover or waist E being formed integral with or attached to the skirt section 10 A', the back opening 22 in this case extending down through the waist and through the skirt down to about the knee, the opening being closed by any suitable means, such as clasps, hooks and eyes, buttons, etc., as 15 clearly shown. It will of course, be understood that the invention may be embodied in various types of union garments adapted for either underwear or outer wear as may be desired.

20 While I have herein shown and described the preferred forms of my invention I wish it to be understood that I do not confine myself to all the precise details of construction herein set forth by way of illustration, 25 as modification and variation may be made without departing from the spirit of the invention or exceeding the scope of the appended claims.

What I claim is:

30 1. A garment of the class described including a skirt having a closed bottom edge portion and leg openings at each side of the skirt extending down to and through the bottom edge portion and separate substantially sheet-like fabric sections attached throughout their top edge portions to the top marginal edges of the leg openings and attached throughout the length of their spaced side edge portions to the side marginal edges of the leg openings, said sections overlying the openings and adapted to partially embrace the limbs of the wearer.

2. A garment of the class described comprising a skirt having a closed bottom edge portion, the material of the skirt at each side thereof having a leg opening defined by a substantially horizontal top marginal edge and inclined vertical marginal edges extending downward to and through the bottom edge of the skirt, and separate flared sections of fabric attached at their top and side edges to the marginal edges of the openings and constituting coverings for such openings, said flared sections of fabric being adapted to partially embrace the limbs of the wearer.

3. A garment of the class described comprising a skirt having a closed bottom edge portion and leg openings at opposite sides 60 of the skirt above the closed bottom edge

portion and extending down to and opening through said bottom edge portion, and separate fabric sections attached to the skirt and constituting coverings for said openings, the bottom edges of said fabric sections being free and lying substantially even with the closed bottom edge of the skirt to form a continuation of such edge, said separate fabric sections being adapted to partially embrace the limbs of the wearer. 65

4. A garment of the class described comprising a skirt having a closed bottom edge portion and leg openings at opposite sides of the skirt contiguous to the closed bottom edge portion, coverings for the leg openings 70 comprising separate sections of material attached to the skirt and overlying such openings adapted to partially embrace the limbs of the wearer, and garter members attached to the inner side of the body of the skirt 75 above the top marginal edges of the openings.

5. A garment of the class described comprising a skirt section and a waist section, said skirt section having a closed bottom 80 edge portion and leg openings formed in opposite sides of the skirt and extending down to and opening through the closed bottom edge portion, and separate fabric coverings for the leg openings attached at 85 their top edge portions to the top marginal edges of the openings and attached throughout the length of their side edge portions to the side marginal edges of the openings, said fabric coverings constituting limb 90 embracing sections in conjunction with the adjacent portions of the skirt. 95

6. As a new article of wearing apparel, a lady's garment having the combined characteristics of a skirt and pantalettes, said garment comprising a piece of material folded upon itself to form a closed bottom edge, the said portions of the piece being cut away laterally and longitudinally to form leg openings extending through the closed bottom edge, the sides of the garment from the top marginal edges of the openings to the waist being closed, one of said folded sections having a placket opening therein, and an inserted leg covering overlying each leg 100 opening and having a free bottom edge terminating substantially in line with the bottom edge of the skirt. 105

In testimony whereof I have hereunto set my hand in presence of two subscribing witnesses. 115

JACOB D. POSNER.
